UNITED STATES PATENT OFFICE.

THOMAS S. REES AND GEORGE C. BROWN, OF RACINE, WISCONSIN.

DRESS MARKER.

Application filed June 14, 1923, Serial No. 645,312. Renewed April 12, 1926.

This invention relates to improvements in dress markers.

It is one of the objects of the present invention to provide a device for use by dress-makers or others when working on wearing apparel by which means a dress or garment may be accurately marked so as to indicate the distance the bottom portion thereof will hang from the floor.

10 A further object of the invention is to provide a device of the class described by which means a circumferential mark may be placed on a garment to indicate where it is to be sewed so that the garment will 15 hang accurately throughout its entire circumference.

15 A further object of the invention is to provide a device of the class described comprising a revoluble platform upon which 20 the person on whom the garment is to be fitted may stand and aid in the marking of the garment by revolving the platform.

25 A further object of the invention is to provide a device of the class described having an adjustable marker to permit a mark being made upon a garment at any desired 30 height from the floor.

30 A further object of the invention is to provide a device of the class described having a graduated marker standard.

35 A further object of the invention is to provide a dress marker which is of very simple construction, is strong and durable, and is well adapted for the purpose desired.

With the above and other objects in view 40 the invention consists of the improved dress marker, its parts and combinations as set forth in the claims, and all equivalents thereof.

Referring now more particularly to the accompanying drawing in which the same reference characters indicate the same parts in all of the views:

Fig. 1 is a longitudinal sectional view of 45 the improved dress marker; parts being broken away; and

Fig. 2 is a plan view thereof, parts being broken away.

Referring to the drawing it will be seen 50 that the numeral 5 indicates the base portion of the improved dress marker, said base portion being adapted to rest upon the floor as indicated by the line 6 in Fig. 1. The upper face of said base portion is provided with an annular grooved flange 7 in which are disposed a plurality of ball bear-

ings 8 placed side by side. Fixedly secured in one side of the base portion, as at 9, is a shaft or rod 10 extending outwardly therefrom and the outer end of said rod is fixedly secured to a standard base 11 which is positioned so as to rest on the floor. Projecting upwardly from the base 11 and at right angles to the face thereof is an elongated standard member 12 of any convenient length, and said standard is graduated as indicated by the lines 13 to indicate inches, centimeters, or any other desired units of measure. A marker arm 14 is pivotally and slidably mounted upon said standard and at right angles thereto and a turn bolt 15 is provided so that said arm may be held at any desired position. The arm 14 is formed in two sections, 16 and 17.

The portion 16 thereof is formed integral 75 with a tubular portion 18 which receives the standard, while the portion 17 thereof serves as an adjustable extension. Said last

mentioned portion has a U-shaped inner end 18 which is adapted to receive the outer end of member 16 and is pivotally secured thereto by means of a bolt 19. The outer end of the arm 17 is provided with a clamping jaw 20 pivotally secured as at 21. A bolt 22 passes through said jaw and the arm, and a nut 23 is provided for the end of said bolt, by which means the jaw may be drawn into close engagement with the adjacent portion of the arm to securely hold a piece of chalk 24 or other marking material as shown.

Projecting upwardly from said base portion 5 and fixedly secured therein is a shaft 25, and lock nuts 26 are provided for the lower end thereof. The upper end of said shaft is journaled in a bearing portion 27 of a platform member 27 which rests on the ball-bearings 8 and is adapted to revolve about said shaft as an axis and move on said ball-bearings. The platform member is 95 somewhat larger in size than the base member and its shape is as shown in Fig. 2. Near the periphery of said platform at one side thereof, a bearing 28 is formed integral with said platform and said bearing has a shaft 29 revolvably journaled therein. The upper end of the shaft has a turn wheel 30 keyed thereto and the portion of the shaft between the bearing and the turn wheel is surrounded by a jacket 31 as shown. The lower end portion of the shaft is threaded as at 32 and a flanged pulley wheel 33 is carried thereon so

as to revolve with said shaft. A nut 34 is provided to hold the pulley wheel in place. An endless belt 35 is further provided and extends around said pulley wheel to, and around the grooved flange portion of the base, as shown.

In use, the person on whom the garment is to be fitted or marked stands upon the central portion of the platform. The standard 10 and marker are then adjusted so that the chalk will describe a line on the garment at the desired height from the face of the platform. Then, the person on the platform may turn the turn wheel slowly. This will 15 revolve shaft 29 and also the pulley 33 carried thereby. As the pulley moves slowly along the inner face of the belt 35, the entire platform will be moved and will roll on the ball-bearings and about the shaft 25 as an 20 axis. As the platform revolves, the person standing thereon will turn with respect to the standard and the marker which are stationary at all times, and the dress-maker or assisting person will cause the garment to 25 brush against the chalk in the marker arm and an accurate, circumferential mark may be described about the garment and wherever desired.

Thus, it will be seen that the improved 30 dress or garment marker can be very easily and accurately operated, is of very simple construction, and is well adapted for the purpose described.

What we claim as our invention is:

35 1. A garment marker, comprising a base member, a platform member rotatably seated on said base member and adapted to have a person stand thereon, said platform member having an integral portion extending laterally beyond the edge of the base member, a 40 shaft rotatably journaled in said extension

portion, a pulley fixedly secured to the end portion of the shaft adjacent the lower face of the platform, an endless flexible means passing around the base member and the pulley, and a wheel keyed to the upper end of the shaft and accessible to a person on said platform for imparting rotation to said pulley whereby said platform will be rotated on the base as said pulley rotates.

2. A garment marker, comprising a stationary base member, a platform member rotatably seated on said base member and adapted to have a person stand thereon, said platform member having an integral portion 55 extending laterally beyond the edge of the base member, a shaft rotatably journaled in said extension portion, a pulley fixedly carried by the end portion of the shaft adjacent the lower face of the platform, an endless flexible belt means passing around the base member and the pulley, a wheel keyed to the upper end of the shaft and accessible to a person on the platform for imparting rotation to said pulley whereby said platform will be revolved on the base as said pulley rotates, a graduated standard member rigidly connected to the base, and a marker arm 60 slidably and adjustably carried by said graduated standard member and cooperating with said revolvable platform for describing a circular mark on the garment of the person on the platform, said marker arm being formed in two sections pivotally joined together and the outer end being provided 65 with a jaw for clamping and engaging a piece of chalk or the like.

In testimony whereof, we affix our signatures.

THOMAS S. REES.
GEORGE O. BROWN.
